UNITED STATES PATENT OFFICE

92,621

DESIGN FOR A WHEELED TOY

Nels H. Nelson, Minneapolis, Minn.

Application April 9, 1934, Serial No. 51,354

Term of patent 14 years

To all whom it may concern:

Be it known that I, NELS H. NELSON, a citizen of the United States, residing at Minneapolis, in the county of Hennepin and State of Minnesota, have invented a new, original, and ornamental Design for Wheeled Toy, of which the following is a specification, reference being had to the accompanying drawing, forming part thereof,

Fig. 1 is a side elevational view; Fig. 2 a front elevational view, and Fig. 3 a rear elevational view of a wheeled toy, showing my new design.

I claim:

The ornamental design for a wheeled toy, as shown.

NELS H. NELSON,
